United States Patent Office.

S. S. DANIELS, OF KENDALLVILLE, INDIANA.

Letters Patent No. 76,059, dated March 31, 1868.

IMPROVEMENT IN MACHINE FOR BENDING CARRIAGE-CIRCLES.

The Schedule referred to in these Letters Patent and making part of the same.

TO ALL WHOM IT MAY CONCERN:

Be it known that I, S. S. DANIELS, of Kendallville, in the county of Noble, and State of Indiana, have invented a new and improved Machine for Beading Carriage-Circles; and I do hereby declare that the following is a full, clear, and exact description thereof, which will enable others skilled in the art to make and use the same, reference being had to the accompanying drawings, forming part of this specification.

Figure 1 is a top or plan view of my improved machine.

Figure 2 is a side view of the same.

Figure 3 is a detail sectional view of the same, taken through the line xx , fig. 1.

Similar letters of reference indicate corresponding parts.

My invention has for its object to furnish a simple, convenient, and effective machine for bending carriage-circles; and it consists in the construction and combination of the various parts, as hereinafter more fully described.

A is the bed-plate or former, which is made with two or more shoulders, a^1 , so as to form portions of different diameters, to adapt it for use in bending carriage-circles of different sizes. The bed-plate or former A is made hollow, to contain water, and is secured in place by bolts passing down through the tubes B, attached to or formed in the said former. C is a clamp, having notches formed in its face corresponding with the shoulders a^1 of the former, A. The stem c' of the clamp C passes down through a hole in the projection a^2 , formed upon the lower part of the said former. To the lower end of the stem c' is pivoted a cam-lever, D, by means of which the clamp C is drawn down, clamping the end of the bar which is to be bent to form the carriage-circle, and holding it securely while being operated upon. E is a slotted and jointed shaft, which passes down through a short tube, F, attached to or formed upon the bottom of the former, A, and is pivoted to said former. G is a lever, the end of which passes through the slot in the shaft E, has a screw-thread cut upon it, and is adjustably secured in place by binding-nuts g' placed upon it, one upon each side of the slotted shaft E. This construction enables the lever G to be adjusted as required for bending circles of different sizes. In that part of the lever G that passes above the shoulders or faces a^1 of the former, A, is formed an upwardly-projecting bend, g^2 , which enables the lever to pass over the clips or feet of the circle being bent. H is the follower, which is made circular in form, and revolves upon a spindle or journal attached to the lever G, as shown in figs. 1 and 2. The follower H is made with a flange upon its face, forming a shoulder corresponding with the shoulders formed upon the face of the former, A. The edge or face of the follower H is recessed or notched at one point, as shown in fig. 1, to enable it to pass over the clamp C without being raised from the former, A. Upon each side of this recess or notch, which is marked h^1 , is formed a smaller notch, h^2 , having a tongue, h^3 , projecting in the centre. The flange of the follower H, upon each side of each of the notches h^2 , is bent or curved upward, as shown in fig. 2. This construction enables the follower H to pass over the clips or feet of the circle being bent, the curves of the flange fitting upon the enlargement of the circle at that point, and the tongue h^3 entering the space between the arms of said clips. To the part of the lever G directly over the edge of the follower H, upon the side of said follower which is nearest the former, A, is attached a segment, g^3 , of a circle, which presses down upon that part of the said follower, and prevents it from being raised by the resistance of the circle being bent.

I claim as new, and desire to secure by Letters Patent—

The combination of the hollow former A, having two or more shoulders, a^1 , formed upon its face, clamp C, cam-lever D, slotted and jointed pivoted shaft E, adjustable lever G, and flanged and recessed followers H with each other, said parts being constructed and arranged substantially as herein shown and described, and for the purpose set forth.

The above specification of my invention signed by me, this ninth day of December, 1867.

S. S. DANIELS.
